ATTORNEY

UNITED STATES PATENT OFFICE.

JAMES JOSEPH MURRAY, OF NEW YORK, N. Y.

AIRPLANE.

1,269,547.

Specification of Letters Patent. Patented June 11, 1918.

Application filed August 17, 1917. Serial No. 186,788.

To all whom it may concern:

Be it known that I, JAMES JOSEPH MURRAY, a citizen of the United States, residing at New York city, in the county of New York and State of New York, have invented new and useful Improvements in Airplanes, of which the following is a specification.

This invention relates to airplanes and particularly to the body construction thereof.

The object of the present invention is to produce a body frame of unusually strong and light construction; also one of which any slack in or distortion of certain parts of the frame may be taken up or compensated for.

A further object of the invention is to provide an airplane body frame embodying certain tensioning and bracing means accessible readily to the operator or mechanic who may in a short space of time, with the aid of a screw driver or the like, place the main members of the body frame under tension and at the same time render the lines of the body true and uniform throughout the entire extent thereof.

With the above and other objects in view, the invention consists in the novel construction, combination and arrangement of parts, herein fully described, illustrated and claimed.

In the accompanying drawings:—

Figure 1 is a side elevation of a sufficient portion of the body of an airplane to illustrate the present invention.

Fig. 2 is a cross section through the same on the line 2—2 of Fig. 1.

The improved body or nacelle is made up of a plurality of hoops 1 each in the form of a true circle and composed of any suitable light tough material such as wood, aluminum, compressed paper or any other material which may be adopted by the manufacturer. In a body of stream line formation, the hoops, which are positioned at intervals throughout the length of the body will vary in diameter in accordance with the stream line formation.

All of the hoops 1 are connected by a circular series of stringers 2 and said stringers are arranged in diametrically opposite pairs and connected by diametrical braces 3 preferably of wire although any desired material may be used in a construction thereof. Each of the stringers 2 is of tubular formation as shown in Fig. 2, com-

prising an outer arcuate wall 4 which conforms in curvature to and lies flush with the outer peripheries of the hoops 1. Each tubular stringer also comprises a reversely curved arcuate inner wall 5 which is shown as substantially semi-circular.

The inner wall of each tubular stringer 4 is formed with a hole 6 to receive a nipple or strainer 7. This nipple or strainer is internally threaded to engage the threaded outer end portion of the respective brace 3 and said nipple or strainer has an enlarged head 8 the under surface of which is rounded or hemispherical to obtain a good seat on the inner surface of the wall 5. The outer wall 4 of the stringer is formed with an entrance opening 9 large enough to admit of the passage therethrough of the nipple 7 and its head 8 until the parts are brought into the associated relation illustrated in the drawings. Any desired number of braces may be used in conjunction with each hoop 1.

From the foregoing description taken in connection with the accompanying drawings it will now be seen that I have produced a body frame for airplanes and other aircraft which is exceedingly strong, thoroughly braced, and of light weight. It will also be seen that any slack or distortion in the frame may be readily corrected by turning the nipples or strainers 7 with the aid of a screw driver or the like inserted through the openings 9. The nipples 7 also perform the additional function of fixedly connecting the hoops 1 and the stringers 4 as said nipples pass through holes formed in each hoop 1. The completed frame is of course intended to be inclosed by a covering or sheathing of fabric or any suitable material, this not being essential to the present invention which relates solely to the construction of the frame of the body or nacelle.

I claim:

1. A body structure for aircraft comprising a plurality of hoops, a series of tubular stringers connecting said hoops at intervals throughout the circumference thereof, said stringers being arranged in diametrically opposite pairs, internally threaded and headed nipples extending through the inner walls of the stringers, and a diametrical brace having its opposite end portions in threaded and adjustable engagement with said nipples.
2. A body structure for aircraft compris-

- ing a plurality of hoops, a series of tubular stringers connecting said hoops at intervals throughout the circumference thereof, said stringers being arranged in diametrically opposite pairs, internally threaded and headed nipples extending through the inner walls of the stringers, and a diametrical brace having its opposite end portions in threaded and adjustable engagement with said nipples, the hoops being formed in their outer peripheries with recesses in which said stringers are seated flush. 25
3. A body structure for aircraft comprising a plurality of hoops, a series of tubular stringers connecting said hoops at intervals throughout the circumference thereof, said stringers being arranged in diametrically opposite pairs, internally threaded and headed nipples extending through the inner walls of the stringers, and a diametrical brace having its opposite end portions in threaded and adjustable engagement with said nipples, each nipple passing through the inner wall of the respective stringer and also through a hole in the adjacent hoop and serving as a means for preventing relative movement between the hoop and stringer. 30
- In testimony whereof I affix my signature.

JAMES JOSEPH MURRAY.
